CONTROL FOR DRAFT REGULATORS

Clarence H. Morrow, Shaker Heights, Ohio, assignor to The Hotstream Heater Company, Cleveland, Ohio, a corporation of Ohio

Application August 15, 1933, Serial No. 685,235

4 Claims. (Cl. 236—45)

This invention relates to means for temporarily closing, as manually, otherwise automatic draft control dampers. In such a draft regulator the shutter has associated weights whereby its opening and closing draft-controlling adjustment is automatic and with predetermined characteristics; and such automatic action is the usual one of the damper. A damper of the class to which reference is had, is illustrated and described in my copending application, Serial No. 658,393, filed February 24, 1933.

Under certain temporary conditions, such as during a firing period, it is necessary that the shutter be closed; and as the regulator is not usually located for convenient direct adjusting access, it is desirable to attach a line leading from the shutter to a position to be grasped by the operator who may thus close the shutter by pulling upon the line.

An arrangement for the purpose is illustrated and described in my copending application, Serial No. 664,793, filed October 6, 1933. Such arrangement is suitable for large regulators but is too expensive to be successfully applied to the smaller sizes.

The objects of the present invention are to provide means for auxiliary manual shutter control, in an otherwise automatic damper by simplified and inexpensive means suitable for smaller sizes of regulators.

Such regulators are usually adapted for installation in either of two positions dependent upon the direction of flow in the flue to be served, the difference in positions being characterized by opposite directions of slope of the shutter axis. A further object of this invention is to provide that the described manual adjustment may be had regardless of the position in which the regulator is installed, so that a single stock form of regulator, with the manual control means, may serve in any installation of proper size regardless of direction of flow.

The exact nature of this invention together with further objects and advantages thereof will be apparent from the following description taken in connection with the accompanying drawing, in which Fig. 1 is a front elevation of a draft regulator embodying the invention, the shutter being shown as closed subject to automatic operation; and Figs. 2 and 3 are enlarged sectional details taken as at lines 2—2 and 3—3 respectively, Fig. 1.

With reference now to the drawing, the principal parts of the damper are an annular base 1

and a shutter 2 adapted to close the opening thereof.

The base 1, preferably a casting as indicated, is adapted to fit within the mouth at the end of the pipe through which flow is to be controlled.

The shutter 2, which may preferably be of sheet metal as indicated, suitably reinforced as by a chordal rib 3 on one side and a diametric rib 4 on the other side and disposed at right angles to the rib 3, is mounted for free swinging movement about a non-diametric chordal axis in the plane of the base, in one direction from said plane. The axis of swing as indicated by the line A—A, Fig. 1, is non-diametric and preferably adjacent the rib 3, and further details of the exact arrangement by which the shutter is mounted are immaterial here, many arrangements for the purpose being well known to those familiar with the art.

The shutter thus has a long side B and a short side C extending from the axis A—A. That the long side B may swing inwardly only, from the plane of the base 1, while the short side C may swing outwardly only therefrom, the base is provided with a flange 5 overlying the side B and a suitable flange underlying the side C.

The shutter is preferably weighted as by a weight 6 mounted upon its back for adjustment along a rod 7, and otherwise forming no part of this invention, to give the predetermined opening and closing characteristics, provided the axis A—A have the proper slope. That this slope may be accurately attained when mounting the device, the front face of base 1 is provided with indexing indicia as indicated at Fig. 1. As appears from these indicia, there are two positions in which the base may be plumbed, the proper position being selected dependent upon the direction of draft in the installation.

What has thus far been described is not new in the art, and it will be appreciated that when properly mounted and adjusted in either of the two positions and under the usual conditions, the shutter will float in partly opened positions automatically adjusting itself to provide the proper flow through the pipe to the end of which it is attached.

According to this invention I provide means for manually closing the shutter when desired.

The principal parts of the structure for this purpose, are an actuator line, guide means therefore and spring means interassociating the line and guide means as will appear.

The guide means comprises as its principal part a tubular guide post 8 having one end rigidly se-

cured with the base 1 as by set screw 9, preferably at a point on the base most removed from the shutter axis A—A, the base having a suitable integral bracket 10 with an opening 11 therein forming a continuation of the opening in the tubular member 8 when the latter is mounted. The arrangement is such that the post 8 extends from the bracket 10, over the shutter face B toward the shutter axis A—A terminating, however, somewhat short of the axis, as indicated Fig. 1. The inner end of the guide post is flared outwardly as at 12 and the opposite end of the opening 11 is chamfered as at 13 so that the guide means described provides a straight through opening having substantially smooth walls throughout, and without sharp edges at the ends.

The actuator line is here shown as a chain 14 of the type whereof each unit has swivel relation with adjacent units, a device preferable because free from twist. However, any freely flexible equivalent such as a light cable or cord might be equally serviceable in some installations. One end of the line 14 is secured to the shutter 2, at a point on the long side B of the latter, opposite the inner extremity 12 of the guide post. Such connection is indicated at 15. The line leads from its connection 15 through the guide means and thence downwardly as at 14a, to a position to be grasped by the operator, where it obviously may be provided with a suitable handle 17.

That the shutter when it is to have automatic operation, may not be unbalanced by the weight of the stretch 14a, which may have considerable length and consequent weight, spring means 18 are provided for yieldably maintaining a bight 14b in the line, effective between the shutter and its guide means. The spring means 18 is a helical wire tension spring arranged within the guide post 8, and about the line 14 extending therethrough. One end of the spring 18 is secured with the line 14 as at 19, intermediate the ends of the guide post, when the parts are positioned as in Fig. 1. The opposite end of the spring 18 is secured to the guide post 8 adjacent the inner extremity of the latter as at 20.

The proportion and arrangement of the parts is such that unless the line be pulled as by the handle 17, the line parts will be positioned generally as in Fig. 1 with a bight 14b adjacent the shutter 2 so that the latter is free to move with automatic operation substantially unaffected by the manually operable parts. Of course, as the shutter moves automatically the bight 14b will be stretched somewhat as the distance between its ends is increased. When, however, it is desired to close the damper, a pull upon the line as by the handle 17 will take up the slack at 14b, against the action of the spring 18, pulling the shutter closed because of the connection of the line therewith at 15.

What I claim is:

1. In an automatic damper of the class described and having an annular base adapted to

be secured to the pipe through which flow is to be controlled, and a shutter mounted in said base for free swinging movement about a chordal axis, a tubular guide post secured on said base on the long side from the shutter axis, and extending inwardly from said base toward the shutter axis, a line having connection with said shutter opposite the inner end of said guide post and leading from the shutter through said guide post and to a position to be grasped by the operator to provide manual closing of the shutter, and means for yieldably maintaining said line slack between said shutter and said guide post to permit automatic adjustment of said shutter.

2. In an automatic damper of the class described and having an annular base adapted to be secured to the pipe through which flow is to be controlled, and a shutter mounted in said base for free swinging movement from the plane thereof, a tubular guide post secured on said base remotely from the shutter axis, and extending inwardly from said base, a line having connection with said shutter opposite the inner end of said guide post and leading from the shutter through said guide post and to a position to be grasped by the operator, and spring means arranged within said guide post to yieldably maintain a slackness of said line between said shutter and said guide post.

3. In an automatic damper of the class described and having an annular base adapted to be secured to the pipe through which flow is to be controlled, and a shutter mounted in said base for free swinging movement from the plane thereof, a tubular guide post secured on said base remotely from the shutter axis, and extending inwardly from said base, a line having connection with said shutter opposite the inner end of said guide post and leading from the shutter through said guide post and to a position to be grasped by the operator, and spring means arranged within said guide post to yieldably maintain a slackness of said line between said shutter and said guide post, said spring means being disposed about said line and having one end connected thereto within the guide post and its other end connected with the guide post adjacent the inner end of the latter.

4. In an automatic damper of the class described and having an annular base adapted to be secured to the pipe through which flow is to be controlled, and a shutter mounted in said base for free swinging movement about a chordal axis, a tubular guide post secured on said base at a point most removed from said axis and extending inwardly from said base in a plane to which said axis is perpendicular, a line having connection with said shutter opposite the inner end of said guide post and leading from the shutter through said guide post and to a position to be grasped by the operator, and means for yieldably maintaining a slack in said line between said shutter and said guide post.

CLARENCE H. MORROW.
